Attorneys

UNITED STATES PATENT OFFICE.

JOE KORKAMES, OF TEMPLE, TEXAS.

TRAY.

Application filed February 26, 1927. Serial No. 171,156.

This invention relates to improvements in trays and more particularly to such as are employed for handling glasses and other containers for drinks and foods,—one object of the invention being to provide a tray of the character specified which shall be sanitary in every respect and which shall be so constructed as to effectually avoid the accidental overturning of glasses or other articles, such as ice cream cones.

A further object is to so construct the tray that it may be applied in a horizontal position to the upper edge portion of an automobile door or the lower portion of the window opening of a door and securely held in such position.

With these and other objects in view, the invention consists in certain novel features of construction and combinations of parts as hereinafter described and pointed out in the claims.

In the accompanying drawings,—

Figure 1 is a view illustrating my improvements.

Figure 2 is a longitudinal sectional view. Figure 3 is a transverse sectional view, and Figure 4 is a detail view.

My improved tray may be constructed of sheet metal, preferably elongated in form and provided at its edges with upturned flanges 2, and the tray may be supported on a table or counter, by means of legs 3 depending from the body of the tray adjacent the corners thereof. These legs may conveniently consist of heavy wire bent into U-shape and having arms or extensions 4—5 disposed against the underside of the body of the tray near the longitudinal edges of the latter and rigidly secured in any suitable manner.

The body of the tray is provided with a plurality of openings 6 for the accommodation of glasses, mugs, cones or similar containers. These openings are surrounded by upwardly projecting sleeves 7 which may be formed integral with the body of the tray by pressing the metal upwardly and said sleeves serve effectually to hold the containers in upright positions and prevent their accidental overturning. Those portions of the tray which are not provided with holders, such as above described, may serve to receive dishes containing ice cream or other food.

A sleeve bracket 8 is secured to the bottom of the tray transversely thereof and

preferably centrally between the ends of the tray. This sleeve is provided with a slotted extension 9 having a plurality of notches 10 in one wall of the slot. A rod 11 is longitudinally movable through the sleeve and is also capable of turning. A clamping head 12 is removably secured to one end of the rod by means of a set screw 13 or in any other suitable manner. The other end of the rod is provided with a handle 14 and also with a removable pin 15 to engage one or another of the notches 10. A spring 16 encircles the slotted extension of the sleeve and bears at one end against one end of the sleeve, abutments 17 being provided at the free end of the extension for the other end of said spring and the removable pin 15 may project between convolutions of said spring.

When the tray is applied to the vertically disposed automobile door or other vertical support, two of the legs will become disposed against one side of the door and the clamping head caused to engage the other side of the door. The tray will therefore be disposed horizontally and will be locked in its attachment to the door by partially rotating the operating rod 11 so that the pin 15 carried thereby will engage in one of the notches 10. When the operating rod is thus turned, it will have a limited rotary movement in the tubular shank 12^a of the clamping head, said shank having a slot 12^b to permit movement of the removable pin or set screw 13. In order to prevent turning movement of the clamping head, the latter may be provided with a flange or foot 12^c to slide against the bottom of the tray.

Should it become desirable to remove the clamping devices for cleaning or for other reason, this may be accomplished by first removing the screw or pins 13 and 15 and the parts may be easily and quickly reassembled.

Having fully described my invention what I claim as new and desire to secure by Letters-Patent, is:

1. The combination with the body of a tray, of a sleeve bracket secured on the underside thereof and provided with a slotted extension having notches in one wall of the slot, an operating rod passing through said sleeve and its extension and movable longitudinally and rotatably with relation thereto, a clamping head on one end of said operating rod, a pin carried by said rod and

adapted to engage one or another of said notches to lock the clamping head in adjusted position, and depending members on said tray beyond respective sides of the 5 clamping head.

2. The combination with a tray, of depending members spaced apart near an edge thereof, of a bracket sleeve secured to the bottom of the tray and provided with a 10 slotted extension having notches in one wall of the slot, an operating rod passing through said sleeve and its extension and movable longitudinally and rotatably relative there-

to, a clamping head with which said rod is 15 rotatively connected, a spring surrounding the sleeve extension and bearing at one end against the sleeve and at the other end, against abutting means on the extension, and a pin carried by said operating rod, passing 20 between convolutions of said spring and adapted to engage one or another of said notches to lock the clamping means in adjusted position.

In testimony whereof, I have signed this specification.

JOE KORKAMES.
